J. H. McClellan,
ATTORNEY.

UNITED STATES PATENT OFFICE

JASPER WHITING, OF DUBLIN, NEW HAMPSHIRE

CONTAINER

Application filed December 31, 1930. Serial No. 505,724.

This invention relates to match boxes, ash trays, and similar articles.

It aims to improve devices of this character with a view to providing an article which will have a wider range of usefulness and will be more convenient to use than prior devices of this general type.

It is a common experience to have a desire to smoke when the only difficulty in satisfying that desire is the fact that there is no place to dispose of burned matches or ashes.

The present invention aims to devise an article which will supply this need, such an article preferably, but not necessarily, being combined with a match box.

The nature of the invention will be readily understood from the following description when read in connection with the accompanying drawing, and the novel features will be particularly pointed out in the appended claims.

In the drawing,

Figure 1 is a perspective view of the parts of a combined match box and ash tray constructed in accordance with this invention;

Figs. 2 and 3 are plan and end views, respectively, of the article shown in Fig. 1;

Fig. 4 is a side view of the device shown in Figs. 1, 2 and 3; and

Figs. 5 and 6 are perspective views of containers embodying features of the invention in a slightly different form.

Referring first to Figs. 1 to 4, inclusive, it will be seen that the article there shown comprises a U-shaped casing, preferably made of resilient sheet metal and including upper and lower walls 2 and 3, respectively, and a bridge 4 connecting said walls. Mounted side by side in this casing are two

boxes 5 and 6, the former preferably consisting merely of a tray or drawer, made of metal, bakelite or other suitable material, and being designed to hold ashes, burned matches, and the like, while the latter consists of a match box of a common form. This box 6 includes a shell *a* and a tray or drawer *b* slideable in the shell, the tray being designed to hold a quantity of matches. One side *c* of the box 6 is coated with a material necessary for or designed to facilitate the

lighting of the matches. Preferably the parts 2 and 3 of the casing are so biased that they tend to spring toward each other, as shown in Fig. 1, so that when the boxes 5 and 6 are in the casing the walls tend to grip both boxes.

At the open side of the casing the edges of the walls 2 and 3 are bent downwardly to provide flanges 7 and 8 which serve as stops to prevent the movement of the boxes laterally through the open side of the casing. A leaf spring 9 is secured to the bridge piece 4 by a rivet 10 and presses both boxes toward the right, Fig. 3, thus holding the box *c* in firm engagement with the flanges 7 and 8. This pressure of the boxes against the flanges is relied upon largely to hold the boxes in their normal positions in the casing.

To open the ash box 5 it is simply pushed in an endwise direction partially out of the casing. In order to retain it normally in its centered position in the casing where the top of the box or drawer is covered by the upper wall 2 of the casing, the spring 9 is provided with two small projections or lugs 12 punched in it and arranged to enter corresponding indentations 13 formed in one side of the box 5.

The match box may be used in the ordinary manner, the drawer or tray *b* being pushed endwise out of the shell and casing, a match removed and scratched on the surface *c*, the tray in the meantime being returned to its closed position. There is some tendency for the shell *a* of the match box to move with the drawer, and in order to overcome this tendency and to hold the match box shell centered in the casing, short lugs or ears 14 are bent over at the ends of both flanges 7 and 8, as shown in the drawing, where they will engage the opposite ends of the shell. These lugs, however, do not project inwardly far enough to obstruct the movement of the drawer *b*.

The invention thus provides a device in which a match box and ash tray are combined in a form very convenient to use and relatively inexpensive to manufacture.

It is contemplated that features of the invention may be embodied in either a match

box or ash tray, one being independent of the other, and such constructions are shown in Figs. 5 and 6.

In Fig. 5 the box 5 is held in a casing 15, 5 U-shaped in form, and having flanges 7' and 8' against which the box is held by a spring 9' which may be like the spring 9 and may cooperate with the box in the same manner as in the construction shown in Figs. 1 to 4, 10 inclusive.

Fig. 6 shows the match box 6 mounted in a U-shaped casing 16 provided with flanges 7' and 8', respectively, and having ears 14' constructed like and serving the same functions as the corresponding parts shown in Fig. 1. A leaf spring 17 similar to the spring 9 presses the box 6 laterally against the flanges 7' and 8'.

Having thus described my invention, what 20 I desire to claim as new is:

1. An article of the character described comprising a U-shaped casing, two boxes located side by side in said casing between the upper and lower walls thereof, each of 25 said boxes comprising a drawer adapted to slide endwise of the casing into open or closed positions, a spring for pressing said boxes toward the open side of the casing, one of said boxes having a side surface exposed 30 at said open side of the casing, and stops at said open side against which the latter of said boxes is held by said spring.

2. An article according to preceding claim 1 characterized by the fact that one of said 35 boxes includes a shell in which its drawer is slidably mounted, and said casing is provided with stops at its opposite ends to engage the shell and hold it against endwise movement.

40 3. An article according to preceding claim 1 characterized by the fact that means associated with the casing holds both boxes normally in a centered relationship to the casing.

45 4. An article of the character described comprising a U-shaped casing, two boxes located side by side in said casing between the upper and lower walls thereof, one of said boxes consisting of a drawer adapted to slide endwise of the casing into an open or closed position and the other consisting of a match 50 box comprising a shell with a drawer slidably mounted in said shell, a spring for pressing said boxes toward the open side of the casing, said match box having a side surface exposed at said open side of the casing, and stops at said open side against which the latter of said boxes is held by said spring.

55 5. An article of the character described comprising a U-shaped casing, an ash tray and a match box located side by side in said casing between the upper and lower walls thereof with one side of said match box exposed at the open side of the casing, and 60 both boxes being slidable endwise relatively

to the casing into open and closed positions.

6. An article of the character described comprising a U-shaped casing including upper and lower walls and a bridge portion connecting them, said casing being open at 70 the side opposite to said bridge portion, a box positioned in said casing and having a side surface exposed at said open side of the casing, said box comprising a shell and a drawer slidable in said shell into open and 75 closed positions, stops at the open side of said casing for preventing said box from sliding sidewise out of the open side of the casing, and a leaf spring interposed between the bridge portion of said casing and said 80 box for holding said box yieldingly against said stops, said spring and said box having cooperating parts for centering the box in said casing.
